UNITED STATES PATENT OFFICE.

AUGUSTUS FRANKLIN THOMPSON, OF HUNTINGTON, WEST VIRGINIA.

GAS BURNER.

Application filed June 11, 1925. Serial No. 36,400.

To all whom it may concern:

Be it known that I, AUGUSTUS F. THOMPSON, a citizen of the United States of America, and a resident of Huntington, county of Cabell, and State of West Virginia, have invented certain new and useful Improvements in Gas Burners, of which the following is a full and clear specification.

This invention relates to that type of Bunsen gas-burner in which the gas is distributed along a series of burners and injected into each of the burners through a perforation in the pipe, the burners being so arranged that the jet of gas draws in the necessary supply of air, as more fully herein-after set forth.

In the drawing—

Fig. 1 is a side elevation, partly in section, showing the essential parts of the burner;

Fig. 2 is a plan view thereof, partly broken away;

Fig. 3 is a vertical sectional view.

In the drawing annexed, 5 designates the gas-supply pipe provided along its top with a series of perforations 6 spaced to inject a jet of gas into upright tubes 7 which are, at their upper ends, adapted to be connected to any suitable burner-tips or mixing-chambers or used as shown, as a multiple Bunsen burner.

The tubes 7 are mounted in a metal bar 8 supported parallel with the supply-tube 5. The support for this tube consists of a pair of goose-necks 9 formed on the ends of the supporting-bar 8 and provided with holes through which the gas-supply tube 5 passes. Each goose-neck is formed by bending down the end of the supporting-bar and then curving it upwardly, the holes for the gas-pipe

being provided in the vertical portions of the goose-neck. This arrangement affords a broad substantial bearing for the gas-pipe and also provides a support for a set-screw 10 tapped through the curved part of the 45 goose-neck and having its upper end bearing against the gas-pipe, to thus lock the gas-pipe removably in position. This removability of the gas-pipe is desirous because of the need for pipes having various-sized jet-openings 6; this makes the gas-pipes interchangeable, enabling me to insert any capacity gas-pipe that may be necessary for the particular burner I am assembling.

As is obvious, air is drawn into each of the burner-tubes 7 by the jet of gas issuing from the gas-pipe, and the gas and air are mixed in the tube and also in the usual mixing-chamber attached to the upper ends of the tubes. 60 To prevent back-firing, I constrict each tube 7 near its base by providing an annular bead 11 therein. Some or all of these beads may be provided with perforations 12 to draw more air into the tubes by the suction 65 created by the upgoing jet, when desired on certain quality of gas.

What I claim as new is:

A gas-burner of the type herein disclosed embodying a bar supporting a plurality of burner-tubes and having each of its ends bent upon itself to form a U-shaped member, the two legs of each of these members being provided with corresponding holes, a supply-pipe extending through said holes, and set-screws for removably holding the gas-pipe in said U-shaped members.

In testimony whereof I hereunto affix my signature.

AUGUSTUS FRANKLIN THOMPSON.
